(57) **CLAIM**

The ornamental design for the trailer hitch mounted flag pole holder, as shown and described.

DESCRIPTION

FIG. 1 is a perspective view of the trailer hitch mounted flag pole holder of this invention;

FIG. 2 is a back view;

FIG. 3 is a front view;

FIG. 4 is a top plan view;

FIG. 5 is a bottom view;

FIG. 6 is a left side view; and,

FIG. 7 is a right side view.
